(57) CLAIM

The ornamental design for a mosquito killer lamp, as shown and described.

DESCRIPTION

FIG. 1 is a first perspective view of a mosquito killer lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the mosquito killer lamp thereof; and,

FIG. 10 is another exploded view of the mosquito killer lamp thereof.

The broken lines shown in the drawings depict portions of the mosquito killer lamp that form no part of the claimed design.
